CLAIM

The ornamental design for a charger, capable of being connected to a cigarette lighter in an automobile, for a radio telephone, as shown and described.

DESCRIPTION

FIG. 1 is a perspective view, taken from the top and front, showing the charger, capable of being connected to a cigarette lighter in an automobile, for a radio telephone of our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof;

FIG. 7 is a rear elevational view thereof; and,

FIG. 8 is a perspective view taken from the rear thereof.

FIG. I

FIG. 2
